CONTROL CIRCUITS FOR VACUUM TUBES

Carl Volz, Penn Township, Allegheny County, Pa.,
assignor to The Union Switch & Signal Company, Swissvale, Pa., a corporation of Pennsylvania

Application April 4, 1944, Serial No. 529,458

7 Claims. (Cl. 250—27)

1

My invention relates to control circuits for vacuum tubes, and more particularly to control circuits for gas tubes.

A bias voltage is often applied to the grid of a vacuum tube to control the operating characteristics of the tube. For example, in gas tubes, such as "thyatron" tubes, a bias voltage is applied to a grid to control the firing of the tube, the tube ordinarily being maintained non-conductive due to the bias voltage, and being fired when such bias voltage is removed or when a control voltage opposes and overcomes the bias voltage. When such an arrangement is used in safety type circuits, such as railway signal and brake control circuits, it is essential to check the bias voltage because a failure of the bias voltage source or a broken circuit element may result in the tube "firing" at a time when no control voltage is applied.

Because of such circumstances, a feature of my invention is the provision of improved control circuits for vacuum tubes.

Another feature of my invention is the provision of novel circuit arrangements to check the bias voltage of a vacuum tube.

A specific feature of my invention is the provision of novel circuit arrangements for checking the bias voltage of a gas tube used in safety circuits such as railway signal and brake control circuits.

Other features, objects and advantages embodying my invention will appear as the specification progresses.

The foregoing features, objects and advantages embodying my invention are accomplished by a vacuum tube circuit arrangement which includes a bias voltage source and the circuits lead to the associated grid element in series with the anode or plate circuit current source. Thus a loss or failure of the bias voltage source or a broken circuit element through which the bias voltage is applied results in an open circuit condition for the anode circuit and the tube cannot be fired, and the load element which is interposed in the anode circuit cannot be energized to effect a control that usually follows the energization of such load element due to a control voltage applied to the tube.

I shall describe several forms of apparatus embodying my invention, and shall then point out the novel feature thereof in claims.

In the accompanying drawings, Fig. 1 is a diagrammatic view showing one form of apparatus embodying my invention when the apparatus is used in railway train brake decelostat equip-

2

ment to prevent slipping of car wheels. Fig. 2 is a diagrammatic view showing another form of apparatus embodying my invention and wherein both half cycles of an alternating current are used to energize the load element, the apparatus being disclosed as used with train brake decelostat equipment. Fig. 3 is a diagrammatic view showing another form of apparatus embodying my invention when two tubes are powered from a common source and control a common load element but each is controlled from an individual control voltage source, the apparatus being disclosed in connection with train brake decelostat equipment. Fig. 4 is a diagrammatic view showing a form of apparatus embodying my invention when two tubes having separate control voltages and load elements are powered through a common transformer, this form of apparatus also being disclosed in connection with railway train brake decelostat equipment. Fig. 5 is a diagrammatic view showing a form of apparatus embodying my invention when direct current sources are employed and the apparatus is used with railway train brake decelostat equipment.

It is to be understood that my invention is of general application and is not limited to train brake decelostat equipment, this one use serving to illustrate the many places where apparatus embodying my invention is useful.

In each of the several views like reference characters designate similar parts.

Referring to Fig. 1, the reference character VI designates a gas tube having an anode 2, a cathode 3, a shield grid 4, a control grid 5 and a filament 6. Power for tube VI is obtained through a transformer T1, a primary winding 7 of which is connected to a suitable source of alternating current indicated in the drawing by its terminals being designated BX and CX. Filament 6 is connected to secondary winding 8 of transformer T1 and tube VI is heated to be in an active condition. A combined anode and shield grid circuit for tube VI can be traced from the right-hand terminal of secondary winding 9 of transformer T1, as viewed in Fig. 1, through wire 10, winding of a magnet valve M1 of a railway car-brake decelostat equipment to be referred to shortly, wire 11, anode 2 of tube VI, intervening tube space to cathode 3 of the tube, wire 12, right-hand terminal of a secondary winding 13 of transformer T1, winding 13 to its left-hand terminal, wire 14, terminal 15 of shield grid 4 of tube VI, and wire 16 to the left-hand terminal 55 of secondary winding 9. It is clear that second-

ary windings 9 and 13 are connected in this circuit in series and are disposed for their instantaneous voltages to oppose each other. Thus, the voltage applied between anode 2 and cathode 3 tending to fire the tube is the resultant voltage of windings 9 and 13, and the shield grid 4 is provided with a bias voltage with respect to cathode 3 which is equal to the voltage created in winding 13. The two windings 9 and 13 are so proportioned that the voltage of winding 9 is relatively large as compared to the voltage provided by winding 13, and there is a resultant voltage applied to anode 2 tending to fire the tube each positive half cycle of the alternating current. It is apparent that during the positive half cycle of the resultant voltage applied to anode 2, the grid 4 is negative in potential with respect to cathode 3, and the instantaneous value of this bias voltage reaches its peak value the instant the anode voltage reaches its peak value. Such a negative bias voltage prevents the tube from firing. Also, during the half cycle the bias voltage applied to grid 4 is positive, the resultant voltage applied to anode 2 is negative with respect to cathode 3 and the tube is not fired. It follows, therefore, that normally the tube V1 is maintained non-conductive due to the bias voltage applied to shield grid 4. The voltages for windings 9 and 13 are preferably pre-selected so that the voltage applied to anode 2 would be just a little below or substantially that required to fire the tube when the bias voltage is withdrawn so that a relatively small control voltage applied to control grid 5 fires the tube. It is apparent also that the bias voltage source from secondary winding 13 is present whenever there is an anode voltage tending to fire the tube because of the series arrangement of the two windings 9 and 13. Furthermore, it is apparent that a break in a circuit element by which the bias voltage is applied, except for a break of grid 4 within the tube V1, causes an open circuit condition for the anode circuit and tube V1 cannot be fired.

Control grid 5 of tube V1 is provided with a circuit including resistors 17 and 20, wire 19 and cathode 3. A condenser 18 and a generator G1 in series are connected across resistor 20. Generator G1 is a direct current generator driven from an axle of a railway car by any one of the several well-known drive mechanisms. For example, generator G1 may be belt connected to the axle. Generator G1 therefore develops a direct voltage, the magnitude of which is proportional to the rate of rotation of the associated wheels and axle unit. It is clear that condenser 18 is charged at a voltage corresponding to the voltage supplied by generator G1 and this voltage across condenser 18 increases and decreases in step with the increase and decrease of the rate of rotation of the wheels and axle unit associated with generator G1. The parts are so proportioned that the usual rate of acceleration and deceleration of the car on which the equipment is mounted is such that the charging current and the discharging current are low and only a small voltage drop is created across resistor 20 due to these currents. However, in case the rate of deceleration of the wheels and axle unit due to an excessive braking condition is of a predetermined value greater than the normal rate the discharge from condenser 18 through resistor 20 is correspondingly large and a relatively high voltage drop is created across resistor 20.

The circuit connection of generator G1 is such

that the polarity of the voltage created thereby is that indicated by the plus and minus signs placed in the drawing, and consequently the voltage drop created across resistor 20 by the discharge of condenser 18 is such that the top terminal of resistor 20 as viewed in Fig. 1 is positive with respect to the lower terminal and the control grid 5 of tube V1 is driven positive in potential with respect to cathode 3 by this control voltage. This control voltage is of a value such that it overcomes the normal bias voltage applied to grid 4, and thus tube V1 is fired when the rate of deceleration of the respective wheels is excessive. With tube V1 fired current flows in the anode circuit each positive half cycle of the alternating current and magnet valve M1 is energized, the energization of magnet valve M1 continuing during the period of discharge from condenser 18. As soon, however, as the control voltage created across resistor 20 by the discharge of condenser 18 ceases, the tube V1 is deionized and magnet valve M1 is deenergized. A condenser C1 is preferably connected across magnet valve M1 to improve the operation.

The decelostat of which magnet valve M1 is a part is of an arrangement that magnet valve M1 when energized cuts off the supply of air pressure to the brake cylinder for the pair of wheels for the wheels and axle unit associated with generator G1, and the brake cylinder is connected to atmosphere to release the brake of that pair of wheels. The parts are so proportioned that the control of tube V1 by the discharge from condenser 18 and the energization of magnet valve M1 continue for a period sufficiently long to assure release of the brake and the wheels permitted to again rotate at the rate corresponding to the rate of rotation of the other wheels of the train.

It is to be seen, therefore, that in Fig. 1, apparatus is disclosed by which a normal bias voltage applied to tube V1 to avoid its firing is checked by a series arrangement of a combined anode and shield grid circuit, and a loss of the bias voltage source or a broken circuit element by which the bias voltage is applied to the tube results in an open circuit condition for the anode circuit and the tube cannot be fired and the load element interposed in the anode circuit cannot be energized.

It should be noted in connection with the apparatus of Fig. 1 that the control voltage can be applied to grid 4 and the normal bias voltage applied to grid 5, and the same operation of the tube effected.

In Fig. 2, equipment to use both half cycles of the alternating current for energizing the load element is disclosed. A second gas tube V2, similar to tube V1, is provided, and the two tubes V1 and V2 are powered through the same transformer T2 and are controlled through the same source of control voltage. A primary winding 38 of transformer T2 is connected to the terminals BX and CX of the alternating current source. Filaments 6 and 25 of tubes V1 and V2, respectively, are connected to secondary winding 39 of transformer T2 to heat the tubes. Since the load element is to be energized by both half cycles of the alternating current and both tubes are to be fired from the same source of control voltage, the voltages applied to the anodes of the two tubes must be of opposite relative polarity. This results in a difference of potential between the cathodes of the two tubes and their control grids 75 cannot be connected to a common control source

except means is provided to make the control grids vary in potential with respect to each other in step with the variation of potential between the two cathodes. Transformer T2 is provided with a secondary winding 26 having a mid terminal for applying to the two tubes anode voltages of opposite relative polarity and with a secondary winding 37 to apply to the control grids of the tubes a voltage that varies with the voltage variation between the two cathodes.

Tube V1 is provided with an anode-shield grid circuit extending from a left-hand terminal of secondary winding 26 through wire 27, anode 2 and tube space to cathode 3 of tube V1, a secondary winding 28 of transformer T2, wire 29, terminal 15 of shield grid 4 of tube V1, wire 30, winding of magnet valve M1 and wire 31 to mid terminal of secondary winding 26. Thus the left-hand portion of secondary winding 26 serves as a source of anode voltage for tube V1 and secondary winding 28 serves as a source of bias voltage for the tube, and these two windings are serially included in the circuit and are connected for their voltages to oppose each other, the parts being proportioned for tube V1 to be normally maintained non-conductive.

Tube V2 is provided with an anode-shield grid circuit extending from the right-hand terminal of secondary winding 26 through wire 32, anode 21 and tube space to cathode 22 of tube V2, secondary winding 33 of transformer T2, wire 34, terminal 35 of shield grid 23 of tube V2, wires 36 and 30, winding of magnet valve M1 and wire 31 to the mid terminal of secondary winding 26. Thus the right-hand portion of secondary winding 26 serves as a source of anode voltage and secondary winding 33 serves as a source of bias voltage for tube V2, the parts being so proportioned and the connection such that the voltages of these two windings oppose each other and the tube V2 is normally maintained non-conductive. Also, it is to be noted that the presence of the bias voltage for tube V2 is checked due to the series connection of the bias voltage winding 33 and the anode voltage winding 26.

It is also to be noted that the two biasing secondary windings 28 and 33 are serially connected between the cathodes 3 and 22 of the two tubes V1 and V2 and consequently there is a difference of potential between these two cathodes equal to the sum of the two bias voltages. Secondary winding 37 of transformer T2 is connected between control grid 5 of tube V1 and control grid 24 of tube V2 and is proportioned and connected so that the value of the voltage supplied to the control grids from secondary winding 37 is equal and is of opposite relative polarity to that existing between the two cathodes due to the series arrangement of the biasing windings 28 and 33. In this way, the control grid of each tube is normally at the same alternating current potential as its cathode. Tubes V1 and V2 are provided with a source of control voltage that includes generator G1, the connection being similar to that shown and described for Fig. 1. That is, generator G1 is driven from an axle of a car truck and serves as a source of control voltage through condenser 18 which is normally charged at a voltage corresponding to that created by generator G1.

Normally, that is, when no effective voltage drop is created across resistor 20 of Fig. 2, both tubes V1 and V2 are non-conductive due to the bias voltage applied to their respective shield grids. In case the wheel of the wheels and axle 75

unit associated with generator G1 are braked excessively and a resultant control voltage is created across resistor 20 due to the discharge of condenser 18, this control voltage is applied to control grid 5 of tube V1 and that tube is fired during the positive half cycles of the voltage applied to its anode 2 and magnet valve M1 is energized by such half cycle of anode current. This control voltage across resistor 20 is also applied across control grid 24 and cathode 22 of tube V2 through windings 31, 33 and 28 and tube V2 is fired during the half cycles of the alternating current that the anode of tube V2 is positive with respect to the cathode and the magnet valve M1 is energized by these half cycle impulses of anode current. Consequently, magnet valve M1 is energized by both half cycles of the alternating current supplied through transformer T2. Magnet valve M1 when energized controls the brake cylinder pressure for the wheels of the wheels and axle unit associated with generator G1, the same as explained in connection with Fig. 1.

It follows that in Fig. 2 there is disclosed apparatus wherewith both tubes V1 and V2 are controlled from the same source of control voltage and the magnet valve M1 included in the anode circuits of both tubes is energized by both half cycles of the alternating current of the power source. Also, the bias voltage source for each tube and the circuit elements by which the bias voltage is applied are checked by the series arrangement of the anode-shield grid circuit of the respective tube.

In Fig. 3, tubes V1 and V2 are powered through a common transformer, and are controlled from separate sources of control voltage to control in turn a common load element. A transformer T3 has a primary winding 60 connected to terminals BX and CX of the alternating current source. Filaments 6 and 25 are connected to secondary winding 61 of transformer T3 to heat tubes V1 and V2. An anode-shield grid circuit for tube V1 can be traced from an adjustable terminal 62 of secondary winding 63 of transformer T3 through winding of magnet valve M1, wire 64, anode 2 and tube space to cathode 3 of tube V1, an adjustable terminal 65 of secondary winding 66 of transformer T3, wire 67, terminal 15 for shield grid 4 of tube V1, wire 36, terminal 35 for shield grid 23 of tube V2 and wire 68 to the left-hand terminal of secondary winding 63. Secondary winding 63 serves as a source of anode voltage and secondary winding 66 serves as a source of bias voltage for tube V1, these secondary windings being disposed to supply to the circuit voltages of opposite relative polarity and of values preselected to give anode 2 a voltage tending to fire the tube and shield grid 4 a bias voltage sufficient to normally maintain the tube non-conductive. The adjustable terminals 62 and 65 would preferably be in the form of multiple taps and serve as an aid in preselecting proper anode and bias voltages for the tube.

Tube V2 has an anode-shield grid circuit including adjustable terminal 62 of secondary winding 63, winding of magnet valve M1, wires 64 and 69, anode 21 and tube space to cathode 22 of tube V2, adjustable terminal 65 and secondary winding 66, wire 67, terminal 15 of grid 4, wire 36, terminal 35 of grid 23 of tube V2 and wire 68 to secondary winding 63. Windings 63 and 66 serve as sources of anode and bias voltages, respectively, for tube V2 in the same manner they did for tube V1.

Control grid 5 of tube V1 of Fig. 3 is governed

by a control voltage developed across resistor 20 due to discharge of condenser 18 which is charged by axle driven generator G1 in the manner explained hereinbefore. A generator G2, similar to generator G1 is driven from a second axle of the truck, a first axle of which truck drives generator G1. Generator G2 is connected to a condenser 41 through a resistor 43 to charge condenser 41 at a voltage proportional to the rate at which the respective wheels and axle unit rotates. Resistor 43 and a resistor 42 form a control grid circuit for tube V2 as will be apparent from an inspection of the drawing. Magnet valve M1 which is the load element for both tubes V1 and V2 control the air pressure supplied to the brake cylinder of the associated truck in the manner explained hereinbefore.

Normally, both tubes V1 and V2 of Fig. 3 are nonconductive and magnet valve M1 is deenergized. In the event the rate of deceleration of either pair of wheels of the truck exceeds the usual rate and slipping of that pair of wheels becomes likely due to the excessive braking of the wheels the voltage drop created across resistor 20 or 43 as the case may be serves to fire the respective tube and magnet valve M1 is energized to release the brakes for that truck.

It follows that each of tubes V1 and V2 of Fig. 3 is provided with a series circuit arrangement by which the normal bias voltage and the circuit elements through which such bias voltage is applied are checked.

In Fig. 4, tubes V1 and V2 have separate sources of control voltages and separate load elements and are powered through a common transformer. Generator G1 of Fig. 4 is driven by the axle of a truck of a car, the same as in previous cases and is associated with the control grid circuit for tube V1 the same as explained in connection with Fig. 1.

Magnet valve M1 which is the load element for tube V1 is used to control the brakes for the wheels of the wheels and axle unit associated with generator G1 the same as in Fig. 1. Generator G2, similar to generator G1, is driven from a second axle of the car truck or from an axle of a second truck of the car and is associated with a control grid circuit for tube V2 and which control grid circuit includes resistors 42 and 43 and condenser 41, the same as in Fig. 3. A magnet valve M2, similar to magnet valve M1, is the load element for tube V2 and magnet M2 controls the brakes for the wheels of the wheels and axle unit associated with generator G2, the same as magnet M1 controls the brakes of the wheels of the wheels and axle unit associated with generator G1.

Tubes V1 and V2 of Fig. 4 are powered through a common transformer T4, a primary winding 40 of which is connected to terminals BX and CX of the alternating current source. Filaments 6 and 25 of Tubes V1 and V2 are heated from a secondary winding 44 of transformer T4. Tube V1 of Fig. 4 is provided with an anode-shield grid circuit that can be traced from an adjustable terminal 45 of a secondary winding 46 of transformer T4 through winding of magnet valve M1, anode 2 and tube space to cathode 3 of tube V1, adjustable terminal 47 of a secondary winding 48 of transformer T4, terminal 15 of shield grid 4 of tube V1, wire 49, terminal 35 of shield grid 22 of tube V2 and wire 50 to the left-hand terminal of secondary winding 46. Secondary windings 46 and 48 are included in this circuit in series and are connected so that their voltages

oppose each other and are proportioned through the adjustable terminals 45 and 47 to provide proper bias and anode voltages for tube V1, the tube V1 normally being maintained non-conductive, the same as explained in the previous cases.

An anode-shield grid circuit for tube V2 extends from an adjustable terminal 51 of secondary winding 46 through winding of magnet valve M2, anode 21 and tube space to cathode 22 of tube V2, adjustable terminal 52 and secondary winding 48, terminal 15, wire 49, terminal 35 of shield grid 23 of tube V2, and wire 50 to the other terminal of secondary winding 46. Secondary windings 46 and 48 are included in this circuit for tube V2 in series and are connected to oppose each other and by means of adjustable terminals 51 and 52 the voltages are proportioned to provide the proper bias voltage and anode voltage for the tube so that tube V2 is normally maintained non-conductive.

Normally, that is, when no effective voltage drop is effected across either resistor 20 or resistor 43, each tube V1 and V2 is non-conductive due to the bias voltage applied to the respective shield grids 4 and 23. In the case the wheels of the wheels and axle unit associated with generator G1 have an excessive rate of deceleration, the control voltage created across resistor 20 is applied to grid 5 of tube V1 and that tube is fired to energize magnet valve M1 and release the brakes in the manner explained hereinbefore. Similarly, if the wheels of the wheels and axle unit associated with generator G2 have an excessive rate of deceleration, a control voltage is created across resistor 43 due to the discharge from condenser 41 and this control voltage is applied to control grid 24 of tube V2 and the tube is fired so that the magnet valve M2 is energized to release the brakes of the respective pair of 40 wheels.

In Fig. 5, the apparatus is similar to the apparatus of Fig. 1, except direct current sources are provided in place of the alternating current source and a condenser means is connected to the anode circuit of tube V1 to at times deionize the tube. Filament 6 of tube V1 is heated from a battery 53. An anode-shield grid circuit for tube V1 comprises positive terminal of a battery 54, winding of a relay R1, anode 2 and tube space to cathode 3 of tube V1, a bias battery 55, wire 56 to terminal 15 of shield grid 4, and wire 57 to the negative terminal of battery 54. Batteries 54 and 55 are poled to oppose each other as indicated by the plus and minus signs placed in the drawing and for battery 55 to provide a preselected negative bias voltage for grid 4 with respect to cathode 3 and for battery 54 to provide a preselected anode voltage. A condenser C2 and an inductance L1 are connected across cathode 3 and anode 2 and condenser C2 is normally charged at a voltage equal to the resultant voltage of the two batteries. Furthermore, condenser C2 and the inductance L1 are proportioned to provide an oscillatory circuit when tube V1 is conductive. 65 Control grid 5 of tube V1 of Fig. 5 is connected to generator G1, the same as in Fig. 1.

Normally, that is, when no effective control voltage is created across resistor 20, tube V1 is non-conductive and relay R1 is deenergized. In 70 the event the wheels of the wheels and axle unit associated with generator G1 have an excessive rate of deceleration and an effective voltage is created across resistor 20, the tube V1 is fired and relay R1 is energized and picked up by the 75 anode current. With relay R1 picked up to close

front contact 58, a simple circuit is completed for magnet valve M1 to be energized from battery 54, magnet valve M1 controlling the release of the brakes of the wheels associated with generator G1 as explained hereinbefore.

When tube V1 is made conductive, the condenser C2 discharges and the tube is deionized in the well-known manner. Relay R1 is now de-energized but this relay is provided with a slow release period so that magnet valve M1 is retained energized for a period sufficient to insure the release of the brakes. In Fig. 5, the condenser 18 would be proportioned so that its discharge period would be just sufficient to effect the firing of tube V1.

It is apparent that in Fig. 5 there is disclosed a series arrangement of the bias and anode voltage sources for a vacuum tube and which arrangement checks the presence of the bias voltage source and the circuit elements through which the bias voltage is applied.

Again, it is to be observed that the circuits here disclosed for vacuum tubes are of general application and are not limited to train brake decelostat equipment but are of specific advantage when applied to such equipment.

Although I have herein shown and described several forms of control circuits for vacuum tubes embodying my invention, it is understood that various changes and modifications may be made therein within the scope of the appended claims without departing from the spirit and scope of my invention.

Having thus described my invention, what I claim is:

1. In combination; a vacuum tube having an anode, a cathode and a first and a second grid; a load element, a power source of energy, a bias source of energy, said power energy source connected between a terminal of said anode and a terminal of said second grid and said bias energy source connected between a terminal of said second grid and a terminal of said cathode to form a series circuit between said anode and cathode, said power energy source and said bias energy source disposed and proportioned to provide a preselected conductive condition of the tube and which condition is checked by said series circuit, said load element interposed in said series circuit to be energized according to the current flowing in said series circuit as determined by the conductive condition of said tube, and a control source of energy connected between a terminal of said first grid and said cathode terminal to at times modify the preselected conductive condition of said tube.

2. In combination; a vacuum tube having an anode, a cathode and a first and a second grid; a load element, a power source of energy, a bias source of energy, said power energy source connected between a terminal of said anode and a terminal of said second grid and said bias energy source connected between said second grid terminal and a terminal of said cathode to form a series circuit between said anode and cathode, said power energy source and said bias energy source having opposing polarities and disposed for said second grid to have a preselected negative potential with respect to said cathode and said anode to have a preselected positive potential with respect to said cathode to preselect the conductive condition of said tube and which condition is checked by said series circuit, said load element interposed in said series circuit and energized according to the conductive condition

of said tube, and a control circuit including a source of control energy connected between a terminal of said first grid and said cathode terminal to control at times the conductive condition of said tube to effect a predetermined energization of said load element.

3. In combination; a gas tube having an anode, a cathode, a control grid and a shield grid; a bias source of electromotive force, a power source of electromotive force; an anode-shield grid circuit for said tube and including a terminal of said cathode, said bias source, a terminal of said shield grid, said power source and a terminal of said anode in the order named; said bias source and said power source poled and proportioned for said shield grid to have a preselected negative potential with respect to said cathode and for said anode to have a preselected positive potential with respect to the cathode to preselect a non-conductive condition of said tube, a load element interposed in said anode-shield grid circuit, and a control circuit including a source of control electromotive force connected between a terminal of said control grid and said cathode terminal to at times fire said tube to effectively energize said load element.

4. In combination; a gas type of vacuum tube having an anode, a cathode, a control grid and a shield grid; a transformer having a primary winding connected to an alternating current source, a first secondary winding of said transformer connected between said anode and said shield grid and a second secondary winding of the transformer connected between said shield grid and said cathode to form a series circuit between said anode and said cathode, said first and second secondary windings connected in said series circuit for their voltages to have opposite relative polarities and proportioned for said tube to be non-conductive, a load element interposed in said series circuit, and a control circuit including a source of control voltage connected between said control grid and said cathode to at times fire said tube to energize said load element.

5. In combination; a gas tube having an anode, a cathode and at least one grid; a transformer having a primary winding connected to a source of alternating current, a first secondary winding of said transformer connected between said anode and said grid and a second secondary winding of the transformer connected between said grid and said cathode to form a series circuit between said anode and cathode and by which circuit said grid is made negative in potential with respect to said cathode during the half cycle of the alternating current said anode is made positive in potential with respect to the cathode for maintaining a normal non-conductive condition of the tube and which condition is checked by said series circuit.

6. In combination; a first and a second gas tube each having an anode, a cathode, a control grid and a shield grid; a load element, a transformer having a primary winding connected to a source of alternating current, a power secondary winding having a mid terminal for said transformer; a first anode-shield grid circuit including in series a terminal of said first tube anode, a first half portion of said power secondary winding, said load element, a terminal of said first tube shield grid, a first bias secondary winding of said transformer and a terminal of said first tube cathode; said first half portion of the power secondary winding and said first bias secondary winding poled for their voltages to have opposite

relative polarities to maintain said first tube non-conductive; a second anode-shield grid circuit including a terminal of said second tube anode, a second half portion of said power secondary winding, said load element, a terminal of said second tube shield grid, a second bias secondary winding of said transformer and a terminal of said second tube cathode; said second half portion of the power secondary winding and said second bias secondary winding poled for their voltages to have opposite relative polarities to maintain said second tube non-conductive, another secondary winding of said transformer connected between the control grids of said tubes to vary the potential of said control grids in step with the variation in potential between said cathodes due to said bias secondary windings, and a control source of electromotive force connected between the control grid and cathode of each of said tubes to at times fire said tubes to energize said load element by both half cycles of said alternating current as supplied by said power secondary winding.

7. In combination; a gas tube having an anode, a cathode, a control grid and a shield grid; a load element, a bias battery, a power battery; an anode-shield grid circuit including in series a terminal of said anode, said load element, said

power battery, a terminal of said shield grid, said bias battery and a terminal of said cathode; said power and bias batteries poled and proportioned to render said shield grid negative in potential with respect to said cathode and to render said anode positive in potential with respect to said cathode, said voltages preselected to maintain said tube non-conductive and said load element de-energized and which conditions are checked by 5 10 15 20 25 said series anode-shield grid circuit, a control circuit including a source of control voltage connected between a terminal of said control grid and said cathode terminal to at times render said control grid positive in potential with respect to the cathode to fire the tube to energize said load element, and means including capacitance connected to said anode-shield grid circuit to de-ionize said tube.
